VENDIBLE COMMODITY PACKAGE

Hiram Morris Hedges, Jacksonville, Fla., assignor of
fifty percent to Edna Beaty, Jacksonville, Fla.

Application November 24, 1953, Serial No. 393,983

1 Claim. (Cl. 99—172)

The present invention relates to containers, wrappers and packages, generally speaking, and has more particular reference to a vendible ready-to-use package containing bakery products, for example, and has more particular reference to facilities embodied therein whereby the encased products may be readily and easily warmed up preparatory to serving the same for consumption.

It is a matter of common knowledge that bakery products such as finger rolls, hamburger buns and other similar edible goods often have to be heated and freshened up so that they are thus rendered more desirable and palatable. Despite efforts to put out carefully wrapped boxes and other containers, especially in the so-called display window category, the products may tend to wither and become slightly stale and when the time comes to place the same on the table for use it is often necessary, as is generally well known, for the housewife to light up the stove oven and thus freshen up the goods for better eating results. It is felt, therefore, that there has long existed the need for packaged goods in this field of endeavor wherein it would be possible to keep the goods right in the package itself without having to remove the wrapper. Confronted with this problem, I have found that it is quite possible to achieve this desirable end.

In carrying out the principles of the instant inventive concept one needs to use steam from a simple source and this is done by boiling water in a sauce pan until the rising steam is suitable for heating the contents of the wrapped package. To the end that the desired results will be aptly attained, the inventive concept therefore has to do with having normally covered vent means in the package, then uncovering the vent means and placing the vented package over the steam column and allowing the steam to enter the package and in a period of less than one minute or so the accumulated steam in the package will recondition the contents and render same in a ready-to-eat condition.

More explicitly, the invention has to do with a vendible commodity and package in the form of a disposable box, the latter having a bottom provided with a steaming vent, ready-to-eat bakery products in said box, and an air-tight protective wrapper completely encasing said box, said wrapper being moisture-proof and otherwise impervious, a portion thereof covering said vent and being rupturable when finger-pressure is brought to bear thereon in alignment with said vent, whereby said vent may be opened up while the rest of the package stays intact and so that steam is allowed to enter the package to heat the contained product to a palatable state.

Novelty is also predicated on the stated construction wherein the box is of the usual display type and is open at the top but is covered by way of the top part of the wrapper which spans the open top and serves as an inspection window, the bottom portion of the wrapper being that which is puncturable by finger-pressure to uncover one or more vents and to thus render the package ready for steaming in the manner already revealed.

Other objects, features and advantages will become

more readily apparent from the following description and the accompanying sheet of drawings.

In the drawings, wherein like numerals are employed to designate like parts throughout the same:

Figure 1 is a perspective view of a package constructed in accordance with the present invention.

Figure 2 is a view on an enlarged scale in section and elevation and showing the package seated atop an open-top sauce pan for purposes of permitting the jets or currents of steam to enter the then uncovered vents for heating the buns or other products.

Referring now to the drawings and with reference to the same in a general way, it will be observed that the container or box, as a unitary item, is denoted (see Fig. 2) by the numeral 4 while the encasing wrapper is denoted by the numeral 6. The wrapper may be of cellophane or an appropriate moisture-proof grade of so-called wax-paper. To this end, the over-all package may be said to resemble any ordinary bakery product found in the present day grocery or similary commodity store. It may be added that the box itself is of an appropriate grade of cardboard or similar disposable material and it comprises a flat bottom 8 and a marginal upstanding wall or rim 10. The box is open and hence the top part of the cellophane or equivalent wrapper which is denoted by the numeral 12 spans the open top and forms a sort of a window through which the contents of the package may be seen and inspected in the usual way. It is to be assumed here that the contents is a bakery product. In fact, in Figure 2, hamburger buns or the like are shown and denoted by the numeral 14. There may be some six or eight of these in the package. The side portions of the wrapper which go over the walls 10 are denoted by the numerals 16 and the main portion of the wrapper is denoted in Figure 2 by the numeral 18. The improvements have to do with forming vent means in the bottom of the box. This could be one hole but is preferably an arrangement of four or more holes or vents. These are denoted by the numerals 20 and it will be seen that they are circumferentially spaced and centrally arranged. This is for proper distribution of the steam which enters for conditioning the rolls. Actually, what is done, is to form tongues 22 and these are struck out and pressed inwardly so that the openings or vents are normally open.

45 This means that the portions of the cellophane wrapper which stretch over the openings or vents tautly as at 24 are the pressure-responsive points. These are intended to be flexible so that by exerting sufficient rupturing pressure of the finger against the wrapper material and pressing it into the uncovered vents, it will burst open and the vent will then be in both the wrapper and the bottom of the box. These combining then opened vents will permit the entry of heat from a suitable source. The heat employed is preferably steam. That is to say, in using the packaged products, it is contemplated that a sauce pan, or the like, A will be placed on a stove B and the water C heated to a boiling point to produce steam with the jets of steam flowing upwardly. Then, by placing the bottom side of the package atop of the rim of the pan the steam currents will pass upwardly in the direction of the arrows as shown in Fig. 2 whereupon in on time at all the products 14 in the package, except the opened vents is otherwise intact, and to thus obtain the desired warming and freshening results. It follows, therefore, that while the package is still covered with said cellophane, the mere placing of the same for steaming over the sauce pan will in the course of four or five seconds or so, result in hot, fresh buns or bakery goods. The idea is to sell the buns or products packaged in the manner shown in the stores already for use. This will result in the saving of time and fuel and avoid having a hot kitchen in the summertime. Such a vendible commodity package.

3

is therefore thought to be unique and worthy of practical adoption and use by container manufacturers, by bakeries, retail stores, and users in general.

From the foregoing, the construction and operation of the device will be readily understood and further explanation is believed to be unnecessary. However, since numerous modifications and changes will readily occur to those skilled in the art, it is not desired to limit the invention to the exact construction shown and described, and accordingly all suitable modifications and equivalents may be resorted to, falling within the scope of the appended claim.

What is claimed as new is as follows:

A vendible commodity protecting and marketing package for ready-to-eat bakery products and wherein the package containing the product lends itself to steaming for purposes of freshening, if necessary, the stated product comprising, in combination, a box open at the top and having a bottom and complementary upstanding marginal walls, said bottom being provided with a plurality of centrally positioned but distributively spaced steam admitting vents, said vents being formed by struck-out individual tongues which are normally flush with the bottom but are susceptible of being forcibly pressed upwardly and into the commodity space of the box in which position the vents are then open and readied for use, ready-to-eat bakery products accessibly contained in said com-

modity space, an imperforate air tight protective wax paper wrapper completely encasing said box, said wrapper being moisture-proof but rupturable under the action of intentionally applied finger pressure, the bottom portion of the wrapper spanning the bottom wall and vents and being readily rupturable when a finger is lined up with a given vent and the cooperating portion of the wrapper is ruptured and the stated finger is pressed against the tongue in a manner to force the same inwardly into the interior of the box whereby one or more of said vents are thus opened up to admit steam into said space, and another portion of said wrapper being substantially transparent and spanning the open top of said box and serving as a so-called inspection window.
